GOLF PRACTICING AND SCORING DEVICE

Christopher W. Deibel, Youngstown, Ohio

Application December 15, 1939, Serial No. 309,390

2 Claims. (Cl. 265—21)

This invention relates to a golf practicing and scoring device.

The principal object of the invention is the provision of a golf practicing device wherein a captive ball is positioned on a suitable driving mat so that the same may be driven therefrom in the conventional manner and the result of the drive determined by a visible indicator actuated by the captive ball.

A further object of this invention is the provision of a golf practicing device comprising a captive ball and a suitable driving mat having a suitable target associated therewith so that the accuracy of the drive may be determined thereby.

A further object of the invention is the provision of a golf practicing and scoring device formed of several portions which may be readily assembled for use and which may be disassembled and packed in a relatively small space.

Specifically, the golf practicing and scoring device shown and described herein comprises a centrally positioned rubber driving mat having a V-shaped groove at one end thereof whereby a captive ball is suitably teed, a captive ball affixed to a suitable length of elastic cable being used. Positioned in front of the driving end of the rubber mat an extensible arm carries a vertical target to provide a means of determining the accuracy of the drive and positioned at the rear of the driving mat portion of the device there is a scoring portion which is connected to the captive ball through the elastic cord. The scoring device registers the approximate yardage of each drive, thus the complete practicing and scoring device enables the golfer to practice accurately directed drives and at the same time determine the approximate length of the drive. The device is formed of several portions to lend portability thereto.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed without departing from the spirit of the invention.

The invention is illustrated in the accompanying drawing, wherein:

Figure 1 is a perspective view of the assembled golf practicing and scoring device showing the various parts in assembled relation.

Figure 2 is an enlarged bottom view of the scoring portion of the device shown in Figure 1.

Figure 3 is an enlarged cross sectional view with parts broken away showing the means of attaching the various portions of the device to one another.

By referring to the drawing and Figure 1 in particular it will be seen that the golf practicing and scoring device comprises a centrally positioned rubber mat 10 which is provided at its front end with a curving V-shaped groove 11 formed between a pair of projections 13 of the rubber mat 10. Leading from the apex of this groove 11 there is a channel 14 formed in the bottom of the rubber mat and extending the complete length of the rubber mat. This channel 14 provides clearance for an elastic cable 15 to one end of which a captive ball 16 is attached. Directly behind the rubber mat 10 there is a scoring portion 17 which comprises in effect an extension of the rubber mat 10 and is formed with a hollow under section 18 through which the elastic cable 15 passes and in which one end of the elastic cable 15 is affixed to a driving bar 19. This driving bar 19 is pivoted at a point 20 to the scoring portion 17 and a guide 21 is provided adjacent the pivot to limit the movement of the driving bar 19. In order that the driving bar 19 may be properly tensioned against the pull of the elastic cable 15 a coil spring 22 is attached to the driving bar 19 and to an end 23 of the scoring portion 17. It will thus be seen that motion imparted to the captive ball 16 will result in motion exerted through the elastic cable 15 and thus move the driving bar 19. Positioned in the scoring portion 17 and extending axially thereof there is a slot 24 in which a suitable indicator 25 is positioned. This indicator 25 may practically comprise a block adapted to straddle the slot 24, the said block being provided with the pointer and preferably provided with a miniature golf ball 26 for appearance's sake. Depending portions 27 insure the placement of the indicator in slidable relation to the slot so that movement exerted by the driving arm 19 will cause the indicator 25 to slide along the slot 24 and indicate the approximate yardage of the drive. This is, of course, actuated when the captive ball is driven from the driving mat 10.

In order that the golfer practicing drives upon this device may determine more accurately the nature and direction of the drive a convenient and practical target taking the form of a relatively short vertical section of thin resilient

steel 28 has been provided which is positioned at some distance in front of the driving mat 10 by means of a hinged arm 29 the innermost end of which is split and adapted to engage slots 30 in the projections 13 of the mat 10. The vertical target 28 is preferably positioned in a block 31 which block 31 is hinged to the outermost end of the arm 29.

By referring to Figure 3 an enlarged sectional view of the method of attachment of the target arm 29 may be seen. Again referring to Figures 1 and 2 it will be seen that a similar means is employed in attaching the scoring portion 17 of the device to the mat portion 10 wherein the extensions 32 having upturned ends engage slots in the end of the mat 10.

It will thus be seen that a golf practicing and scoring device has been provided which will enable the golfer to determine the nature of the drive and the approximate yardage thereof as the scoring portion may be accurately set so that the indicator is relatively accurate in indicating the yardage. For example, if it is determined that a golfer averages 250 yards on his drives he may readily set the tension of the spring 22 so that his average drive upon the device results in the indicator being moved to the 25 yard marking. It will also be seen in connection to the target portion of the device that in place of the hinges provided in the target arm 29 a telescoping arrangement might be substituted such as is shown and described in my co-pending patent application, Serial Number 230,639 filed September 19, 1938.

What I claim is:

1. A golf practicing and scoring device comprising a driving mat having a curved V-shaped groove formed in the front end and a channel formed in the bottom thereof and a scoring por-

tion attached to the back of the said mat and comprising a hollow body portion having a slot longitudinally extending therein, an indicator slidably positioned in the said slot, a driving bar pivoted at one end within the said hollow scoring portion, the free end adapted to engage the said indicator so as to move it along the said slot, yieldable means attached to the said body portion and to the said driving bar for resisting the movement thereof, a rubber ball adapted to tee itself upon the said driving mat at the apex of the said curved groove, an elastic cable attached to the said rubber ball and to the said driving bar so that motion imparted to the said ball will result in movement of the said slidable indicator.

2. A golf practicing and scoring device comprising a driving mat adapted to have a target and a distance measuring structure attached thereto, the said driving mat comprising a suitable rubber mat having a V-shaped groove formed in the front end and a channel formed in the bottom thereof, the distance measuring structure comprising a body portion having a channel formed in the bottom thereof and a slot longitudinally extending therein, an indicator slidably positioned in the said slot, a driving bar pivoted at one end and within the said channel in said body portion, spring means positioned between the said driving bar and body portion for resisting the movement of the driving bar, the free end of the driving bar adapted to engage the said indicator so as to move it along the said slot, a captive ball adapted to tee itself on the said driving mat at the apex of the said V-shaped groove, an elastic cable attached to the said captive ball and to the said driving bar so that motion imparted to the said ball will result in the movement of the said slidable indicator.
